RAIL FASTENING

Jacob Rush Snyder, Cleveland, Ohio

Application March 27, 1945, Serial No. 585,043

1 Claim. (Cl. 238—349)

1

This invention relates to fastenings for railway rails and the like and, more particularly, to an improved construction for rail fastenings of the kind embodying a resilient clamp for yieldingly holding the rail against its support.

In rail fastenings of this kind a screw spike is frequently employed for connecting the clamp with the support and holding the clamp in a flexed condition. Unless some means is provided for automatically determining or obtaining the correct amount of deflection desired for the clamp, the spike may be driven too far or in some cases not far enough into the support or tie by the section hands. If the spike is driven too far it will hold the clamp in a fully flexed condition and the desired resilient holding action of the clamp will not be obtained. On the other hand, if the spike is not driven far enough there is danger that a safe and secure fastening for the rail may not be obtained.

The present invention solves this problem by providing an improved rail fastening of this character in which a gauge member is employed for determining and limiting the extent to which the rail fastener or spike should be driven into the rail support or tie.

Another object of this invention is to provide an improved rail fastening of the character mentioned, in which the gauge means is a member of a simple and economical construction readily insertable into the opening of the clamp so as to cooperate with the fastening member or spike and become a part of the rail fastening.

Other objects and advantages of the present invention will be apparent from the following detailed description and the accompanying sheet of drawings in which

Fig. 1 is a sectional plan view taken on line 1—1 of Fig. 2 and showing one form of rail fastening embodying the present invention.

Fig. 2 is a partial transverse vertical sectional view taken through the fastening on line 2—2 of Fig. 1.

Fig. 3 is a partial sectional plan view on a larger scale and further illustrating the use of the gauge member.

Fig. 4 is a perspective view showing the gauge member in detached relation.

Fig. 5 is a partial sectional plan view similar to Fig. 1 but showing another rail fastening embodying the present invention, the view being taken on line 5—5 of Fig. 6.

Fig. 6 is a partial transverse vertical sectional view taken on line 6—6 of Fig. 5, and

Fig. 7 is a partial sectional plan view on a larger

scale and further illustrating the gauge member as used in the rail fastening of Figs. 5 and 6.

The form of the invention illustrated in Figs. 1 and 2 provides a fastening for yieldingly holding a rail 10 against a support which is here shown as being a tie plate 11 resting on a wooden tie 12. The rail 10 is of a conventional construction which includes the usual head and web portions 10a and 10b and a laterally extending base flange 13. The tie plate 11 is likewise of a conventional construction being an elongated substantially flat metal plate having an upstanding rib 14 extending thereacross in the direction of the rail 10 and forming a shoulder which is engaged by the edge of the flange 13. The tie plate 11 has suitable openings extending there-through which may include one or more substantially square openings 15 extending through the rib 14 and one or more circular openings 16 located laterally outwardly of the rib.

The fastening also includes a resilient clamp 18 having holding and bearing portions 18a and 18b at the inner and outer ends thereof which engage respectively the upper surface of the rail flange 13 and the upper surface of the tie plate 11. The clamp 18 is here shown as comprising a metal plate of single thickness and of a wavy or corrugated cross-sectional shape so that the portion of the clamp extending between the ends 18a and 18b will bridge over the rib 14 and will be in spaced relation above the surface of the tie plate 11. At a point between the ends 18a and 18b the clamp is provided with an opening 19 located so as to overlie the opening 16 of the tie plate and which is somewhat larger in plan dimensions than the opening of the tie plate. For a purpose to be presently explained, a holding recess 20 is formed in the portion of the clamp which defines the edge of the opening 19 and which recess constitutes an outward extension of the main opening 19.

A fastening member 22, which in this instance is in the form of a screw spike, has a stem portion 22a which extends through the opening 19 of the clamp 18 and through the opening 16 of the rail plate 11 into a preformed opening 23 of the tie 12. The spike 22 also has a head 22b whose underside engages one of the upwardly bowed portions of the clamp 18. When the spike is driven into the tie 12 for the proper distance it holds the clamp 18 in a flexed condition so as to apply pressure to the rail flange 13 for yieldingly holding the rail against the tie plate 11 and the tie plate against the tie.

The clamp 18 is here shown as being also pro-

vided with a down-turned partially sheared integral lug 24 which is offset from the opening 19 of the clamp and is preferably located so as to extend downwardly into one of the openings 15 of the tie plate. When the clamp 18 has been secured in position as shown in Figs. 1 and 2 of the drawing, the lug 24 engages a side face of the opening 15 into which it extends and serves to hold the clamp against turning about the axis of the spike 22.

An important feature of the present invention is the provision of the above mentioned gauge member for automatically determining the correct distance to which the spike 22 should be driven into the tie 12. The gauge member employed for this purpose is here shown as being a member or clip 25 which is adapted to be inserted into the opening 19 of the clamp 18 and to form a stop or spacer extending between the upper surface of the tie plate 11 and the underside of the head 22b of the spike. The gauge member 25 may be constructed from metal plate or other suitable material and is curved transversely of its length so as to have a pair of spaced arms 25a and an open transversely curved recess 26 on one side thereof. This gauge member also has a laterally projecting external rib 27 on the side thereof opposite the open recesses 26.

The radius of curvature for the arm portions 25a, and the transversely curved open recesses 26 defined thereby, preferably is such that the gauge member 25 will conform to and be easily insertable into the opening 19 of the clamp 18 and will assume a position in which the stem portion 22a of the spike 22 engages in the open recess 26 and the arms 25a straddle such stem portion. The gauge member is made of a length suitable for the characteristics of the clamp with which it is to be used, so that when the spike has been driven into the tie to the extent permitted by the gauge member, the clamp will have been deflected downwardly the desired amount for exerting the desired pressure on the rail flange. Gauge members of different lengths can be provided and when rail fastenings are being initially assembled, or subsequently adjusted, a gauge member of an appropriate length can be selected by the track worker to produce the holding action desired from the rail clamp.

In forming a rail fastening of the character shown in Figs. 1 and 2, the track worker applies the rail clamp 18 to the tie plate 11 in the position illustrated. The gauge member 25 can then be inserted into the opening 19 and the spike 22 driven into the tie 12 through the openings 19 and 16 to complete the fastening. Preferably, however, the spike 22 is partially driven and before the head 22b engages the clamp 18 the gauge member 25 is inserted into the opening 19. The spike is then driven into the tie to the full extent permitted by the gauge member to complete the fastening.

An important advantage of the gauge member illustrated in the drawings is that the shape and open recess 26 provided for this member permit it to be inserted into the opening of the clamp 18 after the spike has been partially driven. When the gauge member is inserted into the opening of the clamp, either before or during the driving of the spike 22 as just described above, the external rib 27 engages in the holding recess 20 and this engagement causes the gauge member to be held against turning about the stem of the spike and to be maintained in a position in which it will cooperate properly with the surface of the

tie plate 11 and will always be readily visible for inspection purposes. Whenever it is considered desirable to change the length of the gauge member being used, as for example for altering the pressure being exerted on the rail by the clamp, it is only necessary to partially unscrew the spike 22 and after substituting a different gauge member in the opening of the clamp, the spike is again tightened down.

10 Figs. 5 and 6 of the drawing show another rail fastening embodying a gauge member 27' which is substantially identical with the gauge member 25 described above. In this modified form of fastening the rail 28 is held against the tie plate 29 by means of a resilient clamp 30 and a screw spike 31 extending through the clamp and tie plate into the wooden tie 32. The tie plate 29 here shown is also of a conventional construction but is relatively shorter than the tie plate 11 of Figs. 1 and 2.

15 20 25 30 To adapt the clamp 30 for use with this shortened form of tie plate the outer end of the clamp has a reversely bent portion 33 which has a seating or bearing engagement on the surface of the tie plate just outwardly of the opening 34 thereof. This outer end of the clamp 30 is provided with a slot 35 which extends through the doubled portions of the clamp and communicates with the clamp opening 36 through which the spike extends.

35 30 The gauge member 27 is inserted into the opening 36 of the clamp 30 in the same manner as explained above for the gauge member 25 except that the external rib 37 engages in the slot 35 instead of in a holding recess.

40 45 It will be noted that with both forms of clamps shown in the drawing, the gauge member will be retained in position in the openings of the clamps even though the latter are swung about the spikes, as is sometimes done after the spikes have been loosened a few turns, to permit the removal or replacement of the rail. The engagement of the rib of the gauge member in the holding recess or slot of the clamp causes the gauge member to shift with the clamp during such swinging.

From the foregoing description and the accompanying drawing it will now be readily understood that this invention provides an improved rail fastening in which a gauge member employed therein automatically determines and limits the extent to which the fastening member or spike is driven into the rail support or tie for obtaining the correct initial deflection of the clamp.

55 60 65 70 While my invention has been illustrated and described in considerable detail, it will be understood, of course, that it is not to be considered as being correspondingly limited in scope, but should be regarded as including all changes and modifications coming within the scope of the appended claims.

Having thus described my invention, I claim:

In a rail fastening, a support, a rail on said support and having a base flange, a resilient rail-holding clamp having spaced portions engaging said support and said flange and having an opening therein between said portions, a fastener having a stem extending through said opening and connected with said support and a head engaging the clamp and holding the latter in a flexed condition, and a gauge member disposed in and extending through said opening and forming a spacer adapted to be clamped directly between said support and said head for limiting the deflection of the clamp by said fastener, the por-

tion of the clamp defining the edge of said opening having a holding recess therein, said gauge member having an open transversely curved longitudinal recess in one side thereof and a projecting longitudinal rib on the other side thereof and said gauge member being insertable into said opening for engaging its longitudinal recess in straddling relation with the stem of said fastener and engaging said rib in said holding recess.

10 JACOB RUSH SNYDER.
